Term of patent 14 years

Int. Cl. D6—02
U.S. Cl. D15—1

FIG. 1 is a top perspective view of a chair or similar article, showing my new design; and

FIG. 2 is a bottom perspective view thereof from the opposite end.

FIG. 3 is a sectional view of the side member taken on line 3—3 of FIG. 1 and looking in the direction of the arrows thereof.

The drawing shows the chair or similar article broken away to indicate that the structure is of indeterminate length.

I claim:

The ornamental design for a chair or similar article as shown and described.
